JAMES T. DELANEY, OF BRIDGEPORT, CONNECTICUT, ASSIGNOR TO THE EMCA MANUFACTURING COMPANY, OF BRIDGEPORT, CONNECTICUT, A CORPORATION OF CONNECTICUT.

FIRE-ALARM.

1,356,909.

Specification of Letters Patent.

Patented Oct. 26, 1920.

Application filed October 9, 1919. Serial No. 329,476.

To all whom it may concern:

Be it known that I, JAMES T. DELANEY, a citizen of the United States, residing at Bridgeport, county of Fairfield, State of Connecticut, have invented an Improvement 5 in Fire-Alarms, of which the following is a specification.

This invention relates to the class of fire alarms, illustrated and described in patent 10 to Bowman, No. 1,162,020, dated November 30, 1915, said alarms being adapted for general use as in homes, factories, warehouses and garages, in fact wherever life and property are in danger from fire, and the invention 15 has for its object to so change and improve the construction of said alarms as to greatly increase their reliability and render their operation practically certain for a long period of time and without any attention whatever.

With these and other objects in view, I have devised the novel fire alarm which I will now describe referring to the accompanying drawing forming a part of this 25 specification and using reference characters to indicate the several parts.

Figure 1 is a front elevation of my novel alarm as in use;

Fig. 2 a corresponding vertical section; 30 Fig. 3 a view showing the alarm in side elevation and in connection therewith a dia-grammatic view of an electric bell, battery and wiring system; and

Fig. 4 is a detail sectional view on an 35 enlarged scale.

It should be understood that the invention lies in the special heat operated means shown and described for causing any preferred form of signaling apparatus to operate and 40 that it is immaterial so far as the present invention is concerned what special form of electrically operated noise producing or other signaling apparatus is used. In the present instance I have shown an electric bell or buzzer, indicated by 10, a conventional wiring system, indicated by 11, and a battery, indicated by 12.

The parts of my present invention are carried by an insulating base board 13 50 which may be secured in place wherever required.

14 denotes a tubular metallic case having a bottom 15 provided with a relatively large central opening 16. The case is closed by a 55 cap 17 which like the bottom has a rela-

tively large central opening indicated by 18, and comprises a sleeve 19 which is adapted to slide freely within the case, either cap, or case, or both being made of non-oxidizable metal or rendered non-oxidizable so as to insure that the cap will not stick in the case when released. Within the case and compressed between the cap and the bottom is a relatively strong spring 20. The case is provided with one or more holes 60 21 and the sleeve of the cap is retained in the case by suitable low melting material, indicated by 22 which fills the holes and lies in contact with the sleeve. This low melting material may be anything suitable for the 65 use, as sealing wax or a low melting metallic alloy. The case is secured to the base board by means of a suitable clip or bracket 23 which incloses and grips the case and is secured to the base board by screws 24. 70

Above the case is a contact member 25 which may be simply a strip of metal secured to the insulating base board by screws 26. The free end of the strip is bent outward away from the base board and then 80 downward, the opposite edges of the strip being beveled off so as to form an angular tongue 27, which will pass into opening 18 in the cap when the latter is released and engage both sides of the opening, as clearly 85 shown in Fig. 2, thus insuring effective electrical connection. The electric circuit is completed by attaching one of the wires to one of the clip screws 24 and the other wire to one of the retaining screws 26 for the 90 contact member.

The parts will remain in the position shown in Figs. 1, 3 and 4 under ordinary conditions, the circuit being open. A retaining material is used that will melt or 95 soften sufficiently to release the cap at a predetermined temperature. Should the air in the room reach this temperature, from any cause whatever, the melting or softening of the retaining material will release 100 the cap and permit the spring to raise the cap into engagement with the contact member, thus closing the circuit. As the contact member and the sleeve retain the cap in engagement with the case the circuit will 105 remain closed until the alarm has effected its purpose and the circuit is opened again to stop the alarm in the usual manner, which forms no part of the present invention. Wherever required, as in large rooms, the 110

alarms are used in parallel. The effect of the relatively large openings in the bottom of the case and the cap is to start a draft through the case as soon as the temperature 5 in the room commences to rise. This I find a very important advantage in practically insuring the operation of the alarm at the predetermined temperature, and eliminating the danger of premature or delayed operation.

Having thus described my invention, I claim:

1. A fire alarm comprising a case having a hole, a spring in the case, a cap adapted 15 to be raised by the spring and having a sleeve passing within the case and below the hole, low melting retaining material in the hole and in contact with the sleeve, and a contact member adapted to be engaged by 20 the cap when the latter is released through melting of the retaining material, the bottom of the case and cap being provided with openings.

2. A fire alarm comprising a tubular case, a spring therein, a cap adapted to be raised 25 by the spring, low melting retaining material by which the cap is secured to the case and the spring held compressed, and a contact member adapted to be engaged by the cap when the latter is raised by the spring, 30 the bottom of the case and the cap being provided with relatively large openings to insure draft therethrough when the temperature rises.

3. A fire alarm comprising a tubular case, 35 a spring therein, a cap, low melting retaining material between the cap and the case, and a contact member having a downwardly extending beveled edge, the bottom of the case and the cap being provided with openings and the opening in the cap being engaged by the projection on the contact member when the cap is released by melting of the retaining material.

In testimony whereof I affix my signature. 45
JAMES T. DELANEY.
